UNITED STATES PATENT OFFICE.

SAMUEL DOUTHEY McMILLAN, OF LAKE, NORTH CAROLINA, ASSIGNOR OF ONE-HALF TO
FRANK F. CARDWELL, OF RINGGOLD, VIRGINIA.

LOCKING DISPLAY-STAND.

No. 867,996.

Specification of Letters Patent.

Patented Oct. 15, 1907.

Application filed May 24, 1907. Serial No. 375,613.

To all whom it may concern:

Be it known that I, SAMUEL DOUTHEY McMILLAN, a citizen of the United States, residing at Lake, in the county of Davidson and State of North Carolina, have 5 invented a new and useful Locking Display-Stand, of which the following is a specification.

This invention relates to a stand or rack for holding various articles for display or other purposes, and it relates more particularly to a stand provided with a suitable 10 means for locking the articles upon the stand so that they cannot be removed by unauthorized persons.

One of the objects of the invention is to provide a stand of this character having a plurality of hooks for supporting the articles and a common means for simultaneously locking all the hooks. 15

A further object of the invention is to improve and simplify the construction and operation of this class of devices.

With these objects in view, and others, as will appear 20 as the nature of the invention is better understood, the invention comprises the various novel features of construction and arrangement of parts to be hereinafter more fully described and set forth with particularity in the appended claims.

25 In the accompanying drawing, which illustrates one of the embodiments of the invention, Figure 1 is a perspective view of the stand with portions broken away and showing the parts in locked position. Fig. 2 is a longitudinal sectional view, showing the locking part 30 of the stand in unlocked position.

Corresponding parts in the several figures are indicated throughout by similar characters of reference.

Referring to the drawing, 1 and 2 designate respectively an outer and inner tube, which may be of 35 brass or any other suitable material, and are of substantially the same length. The lower end of the outer tube 1 is screw threaded on, or otherwise attached to, a base piece 3, the latter having apertures 4 for receiving screws whereby the supporting tube 1 may be fastened 40 to the floor, or any other means, in an upright position.

At a plurality of suitably spaced points, the outer tube is slotted, as at 5, two or more slots being arranged at the same height. The metal, instead of being entirely cut away to form the slots 5, is permitted to remain and 45 is turned outwardly from the tube to form hooks 6 for receiving the articles desired to be exhibited or hung up. It is obvious, however, that these hooks may be formed separate from the tube and suitably attached thereto.

50 The inner tube 2 is provided with a plurality of keepers 7 whose ends extend through the slots 5 and coöperate with the hooks to retain the articles placed on the latter. By this arrangement, the movement of the inner tube in one direction will simultaneously move 55 the keepers out of engagement with the hooks so that

the articles may be removed or applied, while the movement in the opposite direction will simultaneously set the keepers and thereby lock the devices on the stand. In order to automatically support the keeper carrying tube 2 in a raised position, so that articles can 60 be placed on the hook without the inner tube having to be manually supported or lifted, a compression spring 8 is provided which at one end rests on the base piece 3 and is secured at its other end to the inner tube.

Any suitable locking device may be employed for 65 holding the inner member depressed against the tension of the spring and with the several keepers in engagement with their respective hooks. One of several simple ways of accomplishing this is illustrated in the present instance, the same consisting of a padlock 9 70 having its hasp 10 extending through registering openings 10' in the inner tube and the cap 12, as shown in Fig. 1, so that by simply removing the padlock, the inner tube will automatically rise and disengage the keepers from their hooks. The upper end of the inner 75 tube extends slightly beyond the outer tube and is provided with a knob 13 which affords a convenient handhold whereby the same may be depressed. The keeper 7 may be of any desired construction, such as a strip of metal, an elliptical ring, or other equivalent means riveted to the inner tube and disposed with its length transversely to the axis of the latter and with its extremities passing outwardly or radially through the slots 5 of the outer tube.

From the foregoing description, taken in connection 85 with the accompanying drawing, the advantages of the construction and method of operation will be readily appreciated by the persons who have occasions to use this class of devices. It is obvious that the device may be used for a variety of purposes, as, for instance, as a 90 street exhibitor for merchandise, a coat stand, a grip stand for check rooms, a mail bag rack and the like.

We have described the principle of operation of the invention, together with the apparatus which is now considered to be the best embodiment thereof, but we 95 desire to have it understood that the apparatus shown is merely illustrative and that various changes may be made, when desired, as are within the scope of the invention.

What is claimed is:—

1. The combination of two relatively movable members, a plurality of pairs of oppositely disposed hooks on one of the members, and a plurality of keepers on the other member each of which is arranged with its extremities in coöperative relation with a pair of the hooks adjacent thereto. 105

2. The combination of two relatively movable members oppositely disposed hooks arranged in pairs on one of the members, keepers on the other member having their ends extending in opposite directions therefrom and arranged in coöperative relation with the hooks, an elastic means engaging the keeper carrying member for holding the latter 110

with the keepers thereof out of engagement with the hooks, and a locking device between the two members for holding the keepers in engagement with the hooks.

3. The combination of two relatively movable members arranged one within the other, pairs of diametrically arranged hooks on the outer member, keepers extending in opposite directions from the inner member and arranged in coöperative relation with the hooks, and means for locking the two members together.

10 4. The combination of a tubular member having groups of openings spaced apart along its length, a second member arranged within the first to move longitudinally thereof, hooks on the outer member disposed at the openings, and a plurality of keepers on the inner member arranged 15 with their extremities extending through the openings and coöperating with the hooks.

5. The combination of a tubular member having groups of openings spaced apart along its length, a second member arranged within the first to move longitudinally thereof, hooks on the outer member disposed at the openings, a plurality of keepers on the inner member arranged 20 with their extremities extending through the openings and coöperating with the hooks, a spring arranged to hold the second member in a raised position, and a locking device 25 for holding the said member in a lowered position.

6. The combination of a tubular member having groups of openings spaced apart along its length, a second mem-

ber movably mounted within the first and having its upper end projecting out of the same, a knob on the projecting end of the second member, hooks on the outer member disposed at the openings, a plurality of keepers on the inner member arranged with their extremities extending through the openings and coöperating with the knobs, a spring arranged to hold the second member in a raised position, and a locking device for holding the said second member in a lowered position.

7. The combination of a tubular member having groups of openings, a base piece on which the said member is arranged in an upright position, a second member arranged within the first with its upper end projecting out of the same, keepers on the inner member whose extremities project through the opening of the outer member, hooks on the outer member which are disposed at the openings in coöperative relation with the keepers, a compression spring abutting at one end the base piece and at the other end the inner member, and a locking device for holding the inner member depressed against the tension of the spring.

In testimony that I claim the foregoing as my own, I have hereto affixed my signature in the presence of two witnesses.

SAMUEL DOUTHEY McMILLAN.
